CLAIM

The ornamental design for a multiple beverage holder, as shown and described.

DESCRIPTION

FIG. 1 is a front, right perspective view of my ornamental design for a multiple beverage holder.

FIG. 2 is a front orthographic view thereof.

FIG. 3 is a rear orthographic view thereof.

FIG. 4 is a right side orthographic view thereof.

FIG. 5 is a left side orthographic view thereof.

FIG. 6 is a top plan view thereof; and,

FIG. 7 is bottom plan view thereof.

The structures shown in phantom or broken lines in FIGS. 1-7 form no part of the claimed design and are included only to illustrate an environment.
